UNITED STATES PATENT OFFICE.

JOSEPH D. KALTENBACK AND JOHN STOLL, OF SAN FRANCISCO, CALIFORNIA.

RAZOR ATTACHMENT.

Application filed October 8, 1924. Serial No. 742,456.

Our invention relates to what we have called and styled a lather trap for razors, and particularly to a device for use in connection with safety razors, and an object 5 of the invention is to provide a device of this character which is applicable to a razor without requiring alterations in the construction thereof, and which will function in conjunction with correlated parts of the 10 razor to constitute a trap or receptacle beneath the comb or guard of the razor to catch the accumulated lather as same is removed from the face during the shaving operation.

Another object of the invention is to provide a device of this character which is yieldable with respect to the guard or comb of the razor and provided with surfaces which will not injure the skin of the user 15 during the shaving operation.

Another object of the invention is to provide a device of this character which will yieldingly adapt itself to the guard of the razor when flexing the blade against 20 the guard.

Other features of novelty and utility will obviously appear upon reference to the accompanying drawings and description, wherein—

30 Figure 1 is a perspective view of a razor showing an application of our invention thereto;

Figure 2 is a vertical transverse section therethrough; and

35 Figure 3 is a perspective view of the device detached from the razor.

As our invention is broadly directed to the provision of trap means that may be associated with the blade so as to catch the 40 lather as the blade is moved over the face, we of course do not desire to limit ourselves to the form of razor for which the invention may be used. For the purpose of illustration, we have shown one type of 45 razor which is commonly in use.

The razor herein illustrated consists of a suitable handle 5 having a threaded socket 6 at one end which receives a correspondingly threaded shank 7 on a concavo-convex 50 blade-flexing member 8. This flexing member is of the type that functions in conjunction with a normally flat steel blade 9 which is adapted to be pressed down against the convexed side of the guard 10. 55 This guard is apertured at 11 to receive

the threaded shank 7. In view of this construction, it obviously follows that when the handle is turned with respect to the shank 7, the flat steel blade is adjusted with respect to the comb surfaces 12 of the aforesaid 60 guard 10.

The handle 5 is formed with a substantially spool shaped extension 13 which is flared respectively in two directions from its center. Our attachment consists of a 65 single piece of substantially U-shaped rubber 14 having a base wall 15 apertured at 16 to accommodate the intermediate portion of said spool shaped extension. The attachment is provided with angularly disposed walls 17 whose free edges terminate slightly within the ends of the teeth of the comb portions of the guard 10. These flanges are disposed with respect to the edges of the blade so that the lather trap 70 or space 18 defined by the attachment and the concaved side of the guard 10 will function to accommodate any lather that passes across the edges of the razor and past the guard teeth. The flanges 17 are yieldable 75 against the face of the user so as to not injure the skin when brought in contact therewith.

As stated, the attachment is formed of rubber. This is desirable in order that it 80 will yieldingly accommodate itself to an adjustment of the guard when effectively presenting the cutting edges of the razor against the teeth of the guard. It is not our intention to be so limited, and it shall be 85 understood that the attachment may be made of any suitable well-known material that will accommodate itself to razors of 90 respectively different forms.

From the construction and arrangement 95 of the attachment it follows that as the razor is drawn over the face of the user, the lather, instead of dripping down from the edge of the razor where heretofore it has at times fallen onto the clothing of the user 100 and soiled the clothing, will pass over the edge of the blade, through the spaces between the guard teeth and thence into the trap or space 18.

The attachment is open at its ends, and 105 when desired the user may place the razor under a running faucet so that the collected lather may be quickly and conveniently displaced therefrom.

Aside from constructing the attachment 110

from rubber for the purpose above stated, this is further desirable in that it will not corrode and thereby infections are not so readily set up in the face of the user during the shaving operation.

We claim:

A razor having a blade guard, and a

yieldable lather trap device underlying the guard and adapted to be pressed into yielding engagement with the teeth of the guard 10 near the ends thereof.

JOSEPH D. KALTENBACK.

JOHN STOLL.
